COMBINATIONAL INDEX POINT SORTER

Eugene A. Ford, Binghamton, N. Y., assignor to
 International Business Machines Corporation,
 New York, N. Y., a corporation of New York

Application March 31, 1934, Serial No. 718,349

11 Claims. (Cl. 209—110)

The present invention relates to a sorting machine for record cards and more particularly to a machine for sorting cards having combinational holes to designate characters which are analyzed while the cards are in motion.

An important object of this invention is broadly to sort records bearing combinations of index points to designate letters, numerals, or other characters.

Another object consists in the provision of means for simultaneously analyzing a plurality of index point positions while the card is in motion and controlling sorting paths in accordance with said analysis.

Other objects further are, severally, to provide a single analyzing mechanism for analyzing the record combinations, to provide for selectively analyzing either one of a plurality of index point fields passing successively past the analyzing means, and to provide a novel means for controlling the selection of the sorting path.

Various other objects and advantages of my invention will be obvious from the following particular description of one form of mechanism embodying the invention or from an inspection of the accompanying drawings, and the invention also constitutes certain new and novel features of the construction and combination of parts hereinafter set forth and claimed.

In the drawings:

Fig. 1 illustrates a section through the analyzing and distributing mechanism of a sorter.

Fig. 2 is a top view taken on line 2—2 of Fig. 1.

Fig. 3 is a side view taken on line 3—3 of Fig. 1.

Fig. 4 is a section on line 4—4 of Fig. 3 illustrating the translating mechanism.

Fig. 5 is a developed diagram of the positioned combs of the translating mechanism.

Fig. 6 is a perspective view of the translating mechanism.

Fig. 7 illustrates a record card having combinational index points.

Figs. 8 and 8a illustrate the types of chute blades.

Fig. 9 is a circuit diagram.

Fig. 9a shows the switching mechanism and its coaction with the card contact lever.

In general the machine operates on the record card as follows:

Referring to Fig. 1 the cards are fed one at a time from magazine A through the analyzing mechanism B which is adjusted to read a single selected card column. As the card moves through the analyzing mechanism the analyzing brush 45 55 senses the perforations in the selected card col-

umn simultaneously and in conjunction with contact bars 26 to 31, to complete a circuit which energizes magnets 58 (Fig. 4). Energization of the magnets opens selected guides 56 which lead the card to one of the sorting pockets 51. *Card.*—The record card adapted to be sorted by this machine is illustrated in Fig. 7 and has an upper and lower field, only one of which is analyzed and sorted at one time. The code used is the combinational hole system wherein the characters are designated by either one, two, three, four, or more holes in a single column, although it is understood the card may have other systems of combination hole designations and still be adapted for sorting by this machine. Character R, for example, is represented by a perforation in the 1 position and a perforation in the A position and a perforation in the C position.

Card feeding mechanism.—Referring to Figs. 1 and 2 the mechanism shown is similar to the one described in my United States Patent No. 1,772,180, dated August 5, 1930, and therefore will be explained in the present case only insomuch as is necessary for a proper understanding of the mechanism involved and its function with respect to the new invention. There are provided two picker elements 10 each of which is fastened to a reciprocally movable picker carried 11 which is actuated by means of bars 12. The bars are hinged on their lower ends to an element generally designated at 13 which is fastened to the frame of the machine. Each of the picker carriers 11 has a piece 14 riveted thereto and between this piece and the front piece 15 forming part of carrier 11, the upper head 16 of bar 12 has its fulcrum. The machine frame carries two pairs of guiding pins 17 provided for pressure springs 18 holding each bar 12 in contact with the coordinated cam disk 19 keyed to the shaft 20 driven by a motor through gearing 21. It is obvious that the bars 12 will oscillate in unison with turning of shaft 20 and the pickers 10 will feed the record cards one by one from the stack 18a through the machine. The record cards are fed to the analyzing mechanism B in a manner well known in the art, which controls a translating device and this in turn controls the distributing mechanism in accordance with the combinational index points of the card. The index points are analyzed while the card is in motion by a mechanism similar to the type described in my U. S. Patent No. 1,909,576, dated May 16, 1933, and need only be briefly described herein.

Analyzing mechanism.—The fixed bar 22 (Fig. 1) has a slot in which a cross bar 23 is slidably ar-

ranged. To said bar is fast a sheet metal support 24 having bent up side portions between which are carried an insulating bar 25 having set therein six metallic bars 26 to 31 extending completely across the width of support 24 (see Fig. 2). The metal bars 26 to 31 are spaced in accordance with the index point positions 1, 2, A, B, C, D, indicated in Fig. 7. At one end the metal bars are in contact with contact blades 32 to 37 held in position by plate 38 fastened to the machine. The contact blades are connected with their associated translating magnets 60 (Figs. 4 and 9) and consequently the proper analyzing bars will be permanently connected with their proper associated translating magnets. For analyzing a card the analyzing brush 45 coacts simultaneously with all said analyzing bars the brush being long enough to cover all six index positions of one column in the upper or lower bank and adapted to simultaneously engage all the bars 26 to 31. The brush 45 is carried by a holder 46 which in turn is insertably carried by a support 47. This support may be moved transversely by means of a handle and a worm 48 which coacts with the support 47 to adjust the brush 45 selectively to any desired record column when the worm is turned. Current is supplied to brush 45 by means of a fixed contact bar 49 which contacts with the brush at all times. One end of the bar 49 is connected with the line (Fig. 9) leading to the current source. The brush holding mechanism as used in this machine is also described more fully and claimed in my U. S. Patent No. 1,946,904, dated Feb. 13, 1934 to which reference is herewith made.

When the card while moving past the analyzing brush as the index point positions of a selected column just in line with the conducting bars 26 to 31, an analyzing circuit is initiated and is set in condition to be completed through the card perforations wherever these occur. Current will thereby be sent through translating magnets 60—corresponding to the perforations in the cards. One or more of the translating magnets 60 will be energized and this will cause opening of a sorting path for the record card and the control of the distributing mechanism. The distributing mechanism, well known in the art and explained in the above U. S. Patent No. 1,946,904 referred to, includes a plurality of superimposed sorting blades 50 leading to the various sorting stations 51 for the cards (Figs. 1 and 2). Each of the blades leading to the sorting stations representing A to Q inclusive terminates in a single finger 52 (Fig. 8) and each of the blades leading to the sorting stations representing the remaining alphabetical and other characters, terminates in a double finger 53 (Fig. 8a). The said blades have one or two lifting pins 54 (Figs. 1, 5 and 6) coacting with the respective fingers depending on the type blade. When any of the said fingers are lifted, the blades are caused to be separated into two groups and provide a passageway for the card to the sorting station in the usual well known manner. The lifting pins 54 (Fig. 1) when in a free position are urged upwardly by the spring actuated levers 55 rotatably mounted on rods 56. There is one lever 55 for each pin 54, the levers 55 are staggered in the upper and lower planes as shown so as to be able to position the pins 54 closely to one another.

The lower portion of the pins 54 is provided with slots 57 suitable for the projections 58 on the slideable combs 59 to pass through. The pins 54 are prevented from moving upwardly when

the projections 58 on the combs 59 are positioned in the slots 57 of the said pins.

There are six groups of combs corresponding to the six index positions as indicated on the card in Fig. 7. Groups 1 and 2 have three combs in each group, and groups A, B, C, D, have four combs in each group (Figs. 5 and 6). Each group of combs is held in a locked position by its corresponding group control magnet 60. The combs 59 are mounted one above the other in frame member 68, fastened to one end of the comb is a block 70 (Fig. 4) having a projecting stop 71 slidably mounted in the frame member 68; the comb at the opposite end is extended so that its extremity 72 coacts with the member 68 to maintain the comb in proper alignment. A slot 73 is provided in each comb suitable to receive the bell crank lever 74 rotatably mounted on shaft 75 and positioned by its corresponding cam 76 keyed on shaft 77 (Figs. 3 and 4). A positioning cam 76 and lever 74 is provided for each comb 59, the cams being so arranged that the combs 59 are set in a predetermined position selected by the setting of lever 78 attached to said shaft 77. There are two settings for the lever 78 as indicated, the position N for sorting numeral characters and the position A for sorting alphabetical characters as indicated on the card.

As the cards are fed to the analyzing mechanism B by the feed rollers 61 (Fig. 1) and the particular perforations in the card are sensed by the brush 45 in conjunction with the bars 26 to 31, the magnets 60 are energized by the established circuits, (to be explained later in connection with Fig. 9) the one or more control magnets energized correspond to the particular group index position, namely, groups 1, 2, A, B, C, D to release the particular groups of combs, as follows: The energization of magnet 60 (Fig. 4) mounted on block 68, attracts its armature 62 pivoted at 63 to unlatch plate 64 so as to move to the left about its pivot 65 by virtue of its spring 66 and thus release the locked comb 59 to be able to move in the direction indicated by the arrow through the agency of spring 67. Referring to Fig. 3, it is seen that the plate 64 when unlatched releases or sets free all the combs in the group corresponding to the group control magnet unlatching the said plate 64.

Setting the lever in position A, that is, to sort alphabetical characters the cams 76 are so arranged to position the corresponding bell crank levers 74 so as to lock some of the combs 59 in such a position that the projections 58 on the combs 59 do not interfere with the movement of any of the pins 54. Other levers 74 are so positioned by their respective cams 76 so as to permit the combs 59 to move by virtue of its spring 67 when the comb itself is unlatched by the plate 64.

Referring to Fig. 5 a developed view of the combs 59 indicates their respective positions in regard to the lifting pins 54 when the lever 78 is set in a position for alphabetical sorting. When the group control magnets 60, each particular magnet hereinafter referred to as magnets 60—1, 60—2, 60—A, etc., corresponding to the index point positions 1—2—A, etc., are energized to set the combs in a free position some of the combs will move to the right as indicated in Fig. 5 and others as mentioned before will remain in a locked position because of the setting of levers 74. The movement of the combs 59 to the right as viewed in Fig. 5 is limited by the projection 71 on block 70 fastened to each comb 59 (Fig. 4). It is seen that some of the combs therefore move to the

right (Fig. 5) when released while others will stay in their set position according to the combinational holes of the card. The differential and combinational adjustment of the combs will permit just one pin 54 or two pins 54 (depending on the character to be sorted, see Fig. 5) to be lifted by its spring, namely, the pin or pins corresponding to the meaning of the hole combination while all other pins will be held back by the combs 59. The projections 58 of which while set in the slots 57 of the pins 54 will prevent the pins from moving upwardly. This selection of the pin or pins raises the particular chute blade 58 which permits the card to be fed to the desired pocket 51 by means of feed rollers 88 in the usual well known manner to complete the sorting operation.

In particular, a selection of the alphabetical character "R" will be detailed and is as follows: The combinational code for "R" as indicated in Fig. 7 consists of three perforations, one in the I position, one in the A position and one in the C position. When the card with these perforations is analyzed circuits through magnets 60—1, 60—A, 60—C, are established by the brush 45 contacting the respective contact bars leading to the magnets thus energizing the said magnets (Fig. 9). As explained, the energization of the magnets 60—1, A, and C releases the plates 64 to set free the corresponding groups of combs, namely, the combs 59 in groups I, A and C (see Figs. 4 and 5). The position of the comb 59 is shown in Fig. 5 as positioned by means of lever 78 in its setting A (Fig. 4). As disclosed hereinbefore the setting of lever 78 permits some of the combs to move, others are maintained in a locked position, therefore when the combs in groups I, A and C are released by the corresponding plates 64, the combs 59 move as follows (Fig. 5):

40 In Group 1.—Comb 22 is released and moves to the right as indicated in the figure, and in so doing locks out all the characters without a hole in this position.

Comb 21 is released but does not move since it is in a locked position, but locked so that its setting does not interfere with any of the pin movements.

Comb 20 is released and moves to the right, and in so doing frees all the pins with a hole in the group position.

In Group A.—Comb 16 is released and permitted to move, locking out all the alphabetical characters that do not have a combination in the A position.

55 Combs 15 and 14 are automatically locked in a free position and do not interfere with any pin movements.

Comb 13 is released and permitted to move forward freeing all pins representing characters that have a perforation in the A position.

In Group C.—Comb 8 is released and permitted to move forward locking out all the characters that do not have a combination in the C position.

Combs 7 and 6 are automatically locked in a free position.

Comb 5 is released and permitted to move forward freeing all characters that have a perforation in this position.

Analyzing the position of all the combs in all the groups it will be seen that lifting pins "R" are the only pins free to operate and move upwardly to lift the corresponding chute blade 58 to direct the analyzed card to the correct pocket position corresponding to "R". Fig. 6 shows the combs 59 in the operated position as described

above set so as to release the pins referred to and locking all the other remaining pins in an inoperative position (all the pins 54 are not shown).

After the card has been fed into the proper sorting path the distributing mechanism must be restored. This is effected in the following way: Upon shaft 28 (Fig. 1) is fast cam 85 coacting with connecting arm 86 pivoted to arm 87 mounted on shaft 88. Arm 89 is mounted on the shaft 88 and has an attached cross bar 90 common to all the lifting pins 54 and coacting with a lip 91 of each pin. Spring 92 is provided for the restoring mechanism to hold the same in contact with its cam 85 on shaft 28. During the sorting cycle when the selected combs are positioned so as to set the pins 54 free the cam 85 will displace the arm 89 to rock shaft 88, arm 89 fastened thereto, and cross bar 90 in a clockwise direction to permit the selected pins to be raised by the springs 92 and lift the correct chute blade 58 for the analyzed card to pass into and then transferred to the selected pocket or station.

25 Arm 87 through spring 92 will follow the rotation of cam 85 and in so doing will then rock shaft 88, arm 89 and cross bar 90 in a counterclockwise direction to restore all the raised pins 54 to the normal position. At the same time cam 93 fast on shaft 94 (Figs. 2 and 4) driven by gearing 94a on the main drive shaft, will permit

30 bell crank lever 95 fixed on shaft 97 to be rotated in a counterclockwise direction by the cam follower 98 rotatably mounted on arm 96 following the cam 93 causing the arm 99 with attached cross bar 100 common to all the combs 59 and coacting with the block 70 on each comb to restore all the released combs 59 and thus lock the pins 54 which have been restored shortly before into position. The combs 59 will be restored against the action of springs 67 and latched in normal

35 position by plates 64 immediately after the plates have been restored by arm 101 to which is attached bail 102 common to all plates 64. Arm 101 is fast on shaft 103 (Fig. 3) which is rotated

40 in a counterclockwise direction by link 104 pivoted to one arm of bell crank lever 95 actuated by cam 93 as disclosed above. When the plate 64 is restored against the action of its spring 66 armature

45 62 is restored to latch the plate in position by arm 106 rotatably mounted on shaft 97. Arm 106 is fast on shaft 97 rocked in a counterclockwise direction as explained. When arm 106 moves in

50 a counterclockwise direction arm 105 held in the indicated position in Fig. 4 by extension 107 on arm 106 follows the moved arm 106 under action of spring 108. Attached to arm 105 is a bail 109

55 common to all the armatures 62 and coacting therewith to restore them and latch the said plates 64, and then all the parts are again in normal position and ready for a new sorting cycle.

60 As previously disclosed shifting of lever 78 (Fig. 4) to position A or N controls the sorting of alphabetical or numeral characters respectively. With lever 78 shifted to the numerical sorting position the levers 74 are positioned in a pre-

65 determined position by their respective cams 76 so as to only sort numerals. With the lever 78 in the alphabet sorting position as disclosed only alphabetical characters are sorted. If cards with numerical perforations are analyzed with the 70 lever 78 in A position it is seen from Fig. 5 that all the pins 54 corresponding to the numerical characters are locked out by the combs in groups 1 and 2 and therefore since no perforations occur in index positions 1 and 2 for the numerals, no 75

pins are released when numerical perforations are analyzed with the lever 18 so positioned. The chute blades 50 are so arranged that when a card is analyzed and no pins are released to select a 5 blade the card analyzed is directed by one of the chute blades 50 to a reject pocket 51 or station. Similarly, when the lever 18 is positioned for numerical sorting and a card is analyzed with alphabetical perforations, the energization of 10 either magnets 60—1 or 60—2 will release a comb in the corresponding group to lock all the pins 54 so that a blade is not selected and the card therefore will be directed to the reject pocket.

15 It has been mentioned that with the lever 18 shifted to position A, the sorting of alphabetical characters is effected and that the levers 74 are positioned by the cams 76 to position the combs 59 as shown in Fig. 5. With reference to the 20 same figure, when the lever 18 is shifted to position N to effect numerical sorting, the levers 74 are positioned by the cams 76 to position the combs 59 as follows:

25 Combs 22, 19, 16, 12, 8 and 4 are locked in the positions shown in Fig. 5. Combs 21, 18, 15, 11, 7, and 3 are released and are free to move to the right as viewed in the figure upon energization 30 of the corresponding magnets 60. Combs 20, 17, 13, 9, 5, and 1 are positioned to the left by the levers 74 and locked in the said position so that the pins 54 which are shown blocked are freed so 35 that they may be raised. Combs 14, 10, 6 and 2 are released to be normally positioned to the right as viewed in the figure so that the projections 58 will prevent the positioning of the pins 54. Upon energization of the corresponding magnets 60 these last mentioned combs are free to move to the right as viewed in the figure, thus 40 releasing certain of the said pins 54. It is evident now from the described positioning of the combs for both alphabetical and numerical sorting why certain of the combs such as 1, 2, 5, 6, 9, and 10, etc. are shorter than the others. Some 45 of the shorter combs during alphabetical sorting, such as 2, 6, 10, etc. are locked in the free position shown and others such as 1, 5, 9, etc. are free so that they may be positioned to the right upon energization of the control magnets. However, during numerical sorting, combs 1, 5, 9, etc. 50 are locked in the extreme position to the left and combs 2, 6, 10, etc. are released by levers 74 to be normally positioned to interfere with the corresponding pins, but which may be released further to move to the right to release said pins upon 55 energization of the corresponding control magnets. Thus it is seen that the shorter combs may be maintained in several positions whereas the longer combs are only locked in the position shown in the figure, or freed so that they may move to the right upon energization of the control magnets.

60 The operation of the machine is controlled by contacts 110 (Figs. 9 and 9a) which govern the current circuit. If the tiltably mounted element 111 is rocked to the right the lever 112 will close the contacts 110 and as soon as card feeding has 65 been initiated these contacts will be held closed by the well known card contact lever 113 which is pivotally mounted at 114 and one arm of which passes slightly within the path of the record cards.

70 The contacts 110 will be automatically opened after exhaustion of the card supply through the arm 115 which is pivotally connected to element 75 111 and under the tendency of a spring trying

to move it upwardly which movement is permitted as soon as card lever 113 does not coact with cards running through the machine.

In order to enable selective analyzing of either the upper or lower index point field as shown in 5 the card in Fig. 7 four cams 116, 117, 118, 119 (Fig. 9) are provided coacting with associated contacts 120, 121, 122, 123. The make and break contacts 120 and 121 are so timed with relation to the feeding mechanism that current is supplied to the brushes while the lower card field or position is under the brush while timing of make and break contacts 122 and 123 is such that an instantaneous impulse is supplied to the brush at the moment the upper field is under the brush. 10 Sorting may be effected selectively in either one of said fields by switching lever 124 either to line of contacts 120 and 121 or the line including contacts 122 and 123.

Briefly summarizing the operation of the machine: If the numerals or the alphabetical characters are to be sorted, the adjustable lever 18 (Fig. 4) is set accordingly either in N or A position. The analyzing brush 45 is then adjusted by means of worm 48 (Fig. 1) to position for 20 sensing the desired card column. Current may be supplied from the source to the machine by the main switch 127 (Fig. 9). When the operator closes the contacts in the previously described manner relays 125 and 126 will be energized and will connect the motor 128 with the supply initiating the feeding of the cards by picker 10 into feed rolls 61 which feed the card beneath the analyzing brush 45 in synchronism with rotation of cams 116, 117, 118, 119 so that the brush is 25 sensing the lower field when the respective cams make and break the contacts 120 and 121 and sensing the upper field on the card when contacts 122 and 123 make and break.

The occurrence of combinational perforations 30 in either field in the selected column of the card results in the analyzing brush engaging the corresponding contact bars 26 to 31 (Figs. 1 and 9) simultaneously to complete the energizing circuits of the magnets 60 corresponding to the positions in which the perforations occur. Energization of the magnets 60—1, 60—2, 60—A, 60—B, 60—C and 60—D attracts their respective armatures 62 to unlatch the plates 64 setting free the combs 59 in the respective groups to release a pin 35 or pins corresponding to the character designated by the combination of perforations. The pin or pins contact the respective guide or chute blade 50 providing an entrance for the card which is continuously advanced by the series of spaced 40 rolls 88 till it falls into the sorting pocket 51 communicating with the opened guide. Those cards which are not sorted continue to advance 45 to a reject pocket.

50 While there has been shown and described and pointed out the fundamental novel features of the invention as applied to a single modification, it will be understood that various omissions and substitutions and changes in the form and details of the device illustrated and in its operation may 55 be made by those skilled in the art without departing from the spirit of the invention. It is the intention therefore to be limited only as indicated by the scope of the following claims.

55 What is claimed is as follows:

1. A machine for sorting record cards bearing 60 combinational index point designations representing groups of characters comprising analyzing means, a translating device comprising a plurality of groups of translating units one group 65

being provided for each index point position of the record, a plurality of station guides selecting members controlled by the said translating device, settable means for controlling the position 5 of each of the translating units when different groups of characters are to be sorted, and means controlled, upon the analysis of a character, by said analyzing means for causing certain translating units in the groups corresponding to the 10 index point positions on the card analyzed to render certain selecting members operative and certain selecting members inoperative when the positioning means is set for sorting one group of characters and permitting the same translating units to render different selecting members operative when the positioning means is set for sorting another group of characters.

2. In a sorting machine for record cards bearing combinational index point designations, analyzing means therefor, a translating device comprising a plurality of groups of translating units one group being provided for each index point position of the record, means controlled by the analyzing means to release all of said units in the groups corresponding to the positions of index point designations to be analyzed, and means coacting with said translating units to prevent certain of the said units in the last named groups from being released upon analysis of the index 20 point designations.

3. In a sorting machine for record cards bearing combinational index point designations, analyzing means therefor, a translating device comprising a plurality of groups of translating units one group being provided for each index point position of the record, a plurality of adjustable station guide selecting members controlled by said translating device, means controlled by the analyzing means to release all of said units in the 25 groups corresponding to the positions of index point designations to be analyzed, and means coacting with said translating units to prevent certain of the said units in the last named groups from being released upon analysis of the index point designations but not interfering with the 30 adjustments of said selecting members and permitting certain of said units to be released to allow certain of said selecting members to be adjusted.

4. In a sorting machine for record cards bearing combinational index point designations representing characters, analyzing means therefor, a plurality of guides for leading said cards to different destinations corresponding to the different 35 characters, a translating device comprising a plurality of groups of translating units one group being provided for each index point position of the card, a plurality of movable guide selecting members controlled by said translating device, means controlled by the analyzing means to release all of said units in the groups corresponding to the positions of index point designations to be analyzed, means coacting with said translating units to position certain translating 40 units in the said groups so as not to be released upon analysis of the index point designations but not interfering with the movement of said selecting members and permitting certain of said units to be released upon analysis of said designations, and means in the said released translating units to render the said selecting members movable corresponding to the guide leading to the destination for the character analyzed.

5. A sorting machine for cards bearing combinational index point designations, analyzing

means therefor, a translating device comprising a plurality of groups of movable translating units one group being provided for each index point position of the card, means controlled by the analyzing means to release all of said units in the groups corresponding to the positions of index point designations to be analyzed, and settable means coacting with said translating units to limit their movement when released upon analysis of a card.

6. In a sorting machine for record cards bearing combinational index point designations representing groups of characters, analyzing means therefor, a translating device comprising a plurality of groups of translating units, one group being provided for each index point position of the record, settable means coacting with said translating units to position said units in a predetermined manner for the sorting of a predetermined group of characters.

7. A sorting machine for record cards bearing combinational index point designations representing group characters, analyzing means therefor, a translating device comprising a plurality of groups of translating units one group being provided for each index point position of the record, a plurality of movable station guide selecting members controlled by said translating device, means controlled by the analyzing means to release all of said units in the groups corresponding to the positions of index point designations to be analyzed, means coacting with said translating units to position said units in a predetermined manner for the sorting of a predetermined group of characters, and means in the said units to prevent movement of all said selecting members upon analysis of a card by said analyzing means with designations representing a group of characters dissimilar to the group of characters to be sorted.

8. In a sorting machine for sorting records bearing combinational index point designations comprising an analyzing device, a plurality of guides for leading said records to their destinations, a plurality of guide openers for engaging said guides, slots provided on each of said guide openers, a translating device comprising a plurality of groups of translating units one group provided for each index point position of the record, control members included in each translating unit, a plurality of levers engaging each translating unit to position each said unit so that the control members of certain of said units engage the slots of certain guide openers and so that the control members of other of said units do not engage the slots of other guide openers, and the said units of the translating device controlled by said analyzing means for effecting the selection of guide openers, upon analysis of the record, by the operation of certain of the positioned units.

9. A machine for sorting cards bearing combinational index point designations representing characters comprising analyzing means, a plurality of guides for leading said cards to different destinations corresponding to the different characters, guide selecting members, a plurality of groups of translating units cooperating with said selecting members, a group provided for each index point position and consisting of a plurality of superimposed units and means controlled upon the analysis of a character by said analyzing means for causing certain of the said translating units of the groups corresponding to the index point positions on the analyzed card

to render inoperative said selecting members corresponding to the guides representing characters not having similar index point positions.

10. A machine for sorting cards bearing com-
5 binational index point designations representing characters comprising analyzing means, a plurality of guides for leading said cards to different destinations corresponding to the different characters, guide selecting members, a plurality of groups of translating units cooperating with said selecting members, a group provided for each index point position and comprising a plurality of superimposed units and means controlled upon the analysis of a character by said analyzing
10 means for causing certain of the said units of the groups corresponding to the index point positions on the analyzed card to render operative said selecting members corresponding to the guides representing characters having similar index point
15 positions.

11. A machine for sorting cards bearing com-

binational index point designations representing characters comprising analyzing means, a plurality of guides for leading said cards to different destinations corresponding to the different characters, guide selecting members, a plurality of groups of translating units cooperating with said selecting members, a group provided for each index point position and comprising a plurality of superimposed units, and means controlled upon the analysis of a character by said analyzing means simultaneously causing certain of the said units of the groups corresponding to the index point positions on the analyzed card to render inoperative said selecting members corresponding to the guides representing characters not having similar index point positions and to render operative those selecting members corresponding to the guides representing characters having similar index point positions.
